ATOMIZER

Filed April 3, 1926

WITNESS:

ATTORNEY

UNITED STATES PATENT OFFICE.

ARTHUR J. SHAUKIS, OF HAVERHILL, MASSACHUSETTS.

ATOMIZER.

Application filed April 3, 1926. Serial No. 99,648.

This invention relates to improvements in atomizers, the general object of the invention being to so form the atomizer that it may be operated with one hand, leaving the other hand free.

Another object of the invention is to place the bulb or collapsible member below the liquid container and to support the bulb on a tube which is connected with the base, 10 with means for supporting the container from the top of the tube.

This invention also consists in certain other features of construction and in the combination and arrangement of the several parts, 15 to be hereinafter fully described, illustrated in the accompanying drawings and specifically pointed out in the appended claims.

In describing my invention in detail, reference will be had to the accompanying 20 drawings wherein like characters denote like or corresponding parts throughout the several views, and in which:

Figure 1 is an elevation of the improved atomizer.

25 Figure 2 is a longitudinal sectional view.

Figure 3 is a section on line 3—3 of Figure 2.

Figure 4 is a sectional detail view showing the air valve.

30 Figure 5 is a section on line 5—5 of Figure 4.

Figure 6 is a sectional view showing a slightly different form of head.

In these drawings, 1 indicates a base to 35 which a vertically arranged tube 2 is connected by a nut 3. This tube 2 supports the bulb or collapsible member 4 which has its reduced ends receiving the ends of the tube and ferrules 5 may be placed over the ends 40 of the bulb to strengthen the same and to produce a neat appearance. A short length of tubing 6 is placed in the lower end of the tube 2 and has its upper end shaped to form a seat for a ball valve 7. The tube 2 is cut 45 to produce tongues 8 which are bent inwardly to form a cage for the ball valve. These tongues also leave openings through which air can pass from the tube into the bulb.

50 Other openings 9 are formed in the upper end of the tube so that air can pass from the bulb into said upper end of the tube.

The liquid container is shown at 10 and is preferably formed of glass and of the shape shown in Figures 1 and 2. A tube 11 is

formed with the container and has a part 55 11' which extends beyond the bottom of the container and is designed to fit within the upper end of the tube 2. The upper end of the tube 11 extends within the neck 10' of the container. A cap 12 is cemented to 60 the lower end of the container and rests upon the upper ferrule 5 so that the container is detachably connected with the tube 2 and bulb by the cap and reduced part 11' of the tube 11.

65 A head 13 has a threaded flange 14 for engaging the threaded neck of the container. This head is provided with the usual vent openings 13'' so that air can enter the liquid container to replace the liquid being drawn 70 therefrom. Within this head is located a tubular member 15 which has a depending part fitting over the upper end of the tube 11 and which extends into the upper part 13' of the head which is provided with the 75 ornamental parts 16 and with the nozzle 17 which is supported by the tube 18 from the parts 13'. A tube 19 is connected with the nozzle and passes through the tube 18, the part 13' and the tubular member 15 and has 80 its lower end extending into the tube 11. The tube 18 is in communication with the interior of the part 13' and the bore of the part 15 is also in communication with the interior of the part 13' and said bore is connected by an elbow 20 with a pipe 21 which extends to the bottom of the container.

85 From the foregoing, it will be seen that air will enter the bulb 4 when the same is expanding, through the tube 6 and the openings in the tube 2 and when the bulb is compressed, the air within the same will pass into the tube 2 and as it cannot pass the ball valve 7, it will pass up through the tube 11, through tube 19 and escape from the nozzle 90 17. This will create a suction in the tube 18 and thus liquid will be drawn from the bottom of the container through the tube 21, elbow 20, the bore of part 15 into the tube 18 and thus the liquid will be sprayed from the 95 nozzle.

100 When the container is to be filled, the head is unscrewed from the neck and lifted off, the tube 21 being attached to the head, will be removed with the same. The slip joints between the upper end of the tube 11, the lower end of the tube 19 and the extension of the part 15 will permit these parts to sep-

arate as the head is lifted off. Then the liquid can be poured into the container after which the head is replaced.

As will be seen, the bulb can be manipulated by one hand, thus leaving the other hand free for other purposes, and as I prefer to form the parts as shown in Figures 1 and 2, an attractive and ornamental device is provided.

10 Instead of forming the device with a short nozzle, as shown in Figures 1 and 2, I may provide it with a long nozzle, as shown in Figure 6, where a long tube 22 is carried by the head 13 and the nozzle is attached to this tube. A small tube 23 passes through the tube 22 into the container for permitting the liquid in the confainer to be drawn to the nozzle by the suction created by the passage of air through the tube 22 through the 15 nozzle. The tube 22 is in communication with the bore of the member 15' which is connected with the tube 11" and thus with the bulb, so that when the bulb is manipulated, air will pass from the same through 20 the tube 11", member 15' into tube 22 and thus flow to the nozzle and create a suction in the tube 23 to draw liquid from the container through said tube 23.

It is thought from the foregoing description that the advantages and novel features 25 of my invention will be readily apparent.

I desire it to be understood that I may make changes in the construction and in the

combination and arrangement of the several parts, provided that such changes fall within 35 the scope of the appended claims.

What I claim is:—

1. An atomizer comprising a base, a tube connected therewith, a collapsible member supported by the tube and through which the tube passes, a valve at the lower end of the tube, said tube having openings therein for connecting its interior with the interior of the collapsible member, a liquid container, a tube therein having a lower extension extending into the upper end of the first tube, a removable head for the container, a nozzle carried thereby, means for connecting the nozzle with the tube in the container and means for connecting the nozzle with the 50 lower part of the container.

2. An atomizer comprising a base, a tubular upright part supported by the base, a collapsible member supported by the lower part of the tubular part and being in communication with said part, a container on the upper portion of the tubular part, a nozzle associated with the container and having a part in communication with the upper end of the tubular part, a tube in communication with the nozzle and extending into the container and valved means for admitting air 60 into the collapsible member.

In testimony whereof, I affix my signature.

ARTHUR J. SHAUKIS.
